UNITED STATES PATENT OFFICE

2,519,405

FILE FOLDER

Charles I. Schwinger, Berwyn, Md.

Application October 30, 1945, Serial No. 625,669

3 Claims. (Cl. 229—72)

(Granted under the act of March 3, 1883, as
amended April 30, 1928; 370 O. G. 757)

1

The invention described herein may be manufactured and used by or for the Government for governmental purposes, without payment to me of any royalty thereon.

This invention relates to a filing device and more particularly to a folder or file for containing records and the like.

The primary object of the invention is to provide a folder or file having expandable pockets or retainers adapted to hold records and the like in a snug manner, and to prevent the data from falling out of the folder, while at the same time supporting the data so that it may be available for reference purposes without removing it or the other data.

Another object is the provision in a device of the class described of expandable pockets for containing data and an expandable front wall member adapted to be retained in alignment with the body of the folder whether the pockets are full or empty or in any intermediate condition.

Another object of the invention is to provide a folder which may be used by lawyers, salesmen, etc., not only as a case for carrying various data but also to provide a filing space in cabinets whereby considerable space and saving may be had by the use of less filing cabinets.

Another object of the invention is to provide a folder of the class described which is simple and cheap in construction, and easy to manufacture.

With the above and other objects and advantages in view the invention consists of certain features of construction and operation of parts which will hereinafter be described and shown in the accompanying drawings in which:

Fig. 1 is a perspective view of the folder in open position showing the inside thereof, with expandable pockets;

Fig. 2 is a fragmentary exploded view of the folder, with front and rear portions thereof separated from the expandable pockets of the folder;

Fig. 3 is a plan view of a blank for forming a gusset used in carrying out the invention;

Fig. 4 is a vertical sectional view taken on line 4—4 of Fig. 1;

Fig. 5 is a fragmentary sectional view taken on line 5—5 of Fig. 1; and

Fig. 6 is a fragmentary perspective sectional detail view of a portion of the folder.

Referring more particularly to the drawings wherein similar reference characters are used to denote corresponding parts throughout, the file folder indicated generally by F may be made of any suitable material known in the art, preferably fiber board, and comprises a front wall portion or panel 2 having an integral cover or flap 3 hinged at 4 adjacent the upper end thereof. The front wall panel 2 of the folder is provided with

2

a central reinforcing sheet 5 which overlies and is adhesively united to the inner side of the wall panel 2, with the reinforcing sheet 5 extending from the bottom edge 6 of the wall panel 2 up to the hinge 4, thereby stiffening the front wall portion 2 and causing it to remain rigid at all times. On the inner side of the reinforcing sheet 5 is a plurality of expandable pockets 7 formed of a wall panel 8 provided with a reinforcing sheet 9, both of which have curved indentations or recesses 10 on their upper longitudinal edges providing spaced upwardly projecting ribs 11. The front portion 2 and wall panel 8 with their reinforcing sheets 5 and 9 are joined along the marginal portions of their sides and bottoms by means of a gusset 12, preferably of a bellows or accordion-like form as illustrated and is therefore expandable. The side ends 12' of the gusset 12 are provided with side marginal flanges 13 and 13' and its bottom portion 14 is provided with marginal flanges 14'. The side flanges 13 of the gusset 12 are adhesively united to and between the side marginal portions of the front panel 2 and reinforcing sheet 5 and the side flanges 13' are adhesively united to and between the side marginal edges of the wall panel 8, and its reinforcing sheet 9, as more particularly shown in Figs. 1 and 2, with the flanges 14' on the bottom of the gusset 12 being adhesively secured to and between the bottom marginal portions of the front panel 2 and reinforcing sheet 5 and between panel 8 and its reinforcing sheet 9. The folder F is provided with corrugated expandable members 15 providing transverse partitions which form sides of an expandable pocket 7, with the sides 12' of the gusset 12 also forming sides of other pockets 7'. These expandable partitions 15 extend in spaced relation vertically upward in alignment with the projecting ribs 11 of the wall panel 8 and reinforcing sheet 9 and are adhesively united by inturned vertical marginal edges 15' to the reinforcing sheet 5 of the front panel 2 and the reinforcing sheet 9 of the wall panel 8. The expandable members 15 are provided at their lower ends with V-shaped notches 16 which engage with the plaited bottom portion 14 of the gusset 12.

A back panel or wall portion 17 of the folder is provided with an adhesively united reinforcing sheet 18, both of which are united by the fluted expandable member 19, including marginal flanges 20 and 20' to the wall panel 8, with the flange 20 of the expandable member 19 being adhesively united to the lower marginal edge of the wall panel 8 and the flange 20' thereof being positioned between the lower inside marginal edges of and adhesively united to the back panel 17 and its reinforcing sheet 18.

A paper fastener 21 of any suitable type and of any suitable material such as a metal Acco fas-

tener is mounted in vertical arranged holes 22 formed in one side of the back panel 17 and its reinforcing sheet 18.

Reinforcing strips 23 of any suitable material such as fabric are provided on the upper inner marginal edges of the sides of the gusset 12 and along the upper marginal edges of the fluted pocket partitions 15.

In order that the folder F may be used as an individual carrying case, it may be provided with any suitable standard means for securing the flap 3 to the back panel 17. In the present case the securing means is illustrated as being in the form of a string 24 secured at one end to the flap 3, and adapted to be wrapped around the disc 25 mounted on the back panel 17.

In operation, the data to be filed away in the folder or to be individually carried therein is placed in the expansible pockets 7 and 7'. As the data accumulates in the pockets 7, the pockets are pushed out or expanded by means of the gusset 12 and the corrugated expansible partition members 15. With the fluted member 19 uniting the back panel 17 and its reinforcing sheet 18 to the wall panel 8, the back panel 17 is also caused to automatically expand, with the pockets 7 as the data is placed therein.

By means of the gusset 12 the front panel 2 of the folder F is kept in alignment with the wall panel 8 as the pockets 7 are being filled with data, thereby avoiding any tendency of the front panel 2 from sagging out of line with the wall panel 8, which would produce an unsightly or awkward file, particularly where it is used for desk or like purposes where an attractive and practical file is desired. The paper fastener 21 permits sheets of correspondence and the like to be connected to the back panel 17 of the folder and referred to, removed therefrom, or additional correspondence placed in the folder, with the fluted member 19 permitting the front portion of the folder to be pushed forwardly as the correspondence is placed on the fastener 21.

To refer to any particular data placed in the pockets 7 of the folder it is not necessary to remove all of the data therefrom but only necessary to pick out the desired data by grasping the top of the data with the hand. The desired data may be inspected or removed from the pockets 7 without disturbing the other data. The curved indentations or recesses 10 of the wall panel 8 and its reinforcing strip 9 permit the data to be inspected without lifting or pulling the data up to find the desired part thereof. The flap 3 on the front panel 2 of the folder is adapted to be closed over the pockets 7 and to extend a predetermined distance over the rear panel 17 where it may be secured thereto by the string 24 engaging the disc 25.

Having thus described my invention, what I claim as new and wish to secure by Letters Patent is:

1. An envelope type record folder comprising an expansible envelope compartment including oppositely disposed panels, and accordion-pleated gussets connecting the panels and closing the panels on all sides except one to form an open envelope compartment, an additional flat paper-receiving panel hingedly mounted on the envelope compartment exteriorly thereof along the lower edge only, said last hinge means comprising accordion-pleated gussets connecting the paper-receiving panel to the envelope compartment.

ment, the paper-receiving panel being adapted to receive papers without obstructing access to the envelope compartment, and a closure flap hingedly mounted on one of the envelope panels 5 along the open edge thereof, the said flap being adapted to close selectively the envelope compartment only and the envelope compartment together with the paper-receiving panel.

2. A record folder comprising an envelope compartment having opposite panels, one of which panels is an outer panel, and another of which panels is an inner panel, accordion-pleated gussets connecting the panels, a substantially flat paper-receiving panel in addition to the panels 15 of the envelope compartment, and expansible hinge means secured to the inner panel of the envelope compartment along the lower edge only, said last hinge means comprising accordion pleats also secured to the flat paper-receiving panel, whereby the said panel is adjustably connected to the envelope compartment, the envelope compartment being open along one side thereof, and a closure flap mounted on the outside panel of the envelope compartment adapted to 20 close selectively, the envelope compartment only and both the envelope compartment and the paper-receiving panel.

3. A record folder comprising an envelope compartment having opposite panels, one of which 30 panels is an outer panel, and another of which panels is an inner panel, accordion-pleated gussets connecting the panels, a substantially flat paper-receiving panel in addition to the panels of the envelope compartment, and expansible hinge means secured to the inner panel of the envelope compartment along the lower edge only, said last hinge means comprising accordion pleats also secured to the flat paper-receiving panel, whereby the said paper-receiving panel 40 is adjustably connected to the envelope compartment while being independent thereof, the envelope compartment being open along a longitudinal side thereof opposite to the accordion-pleated hinge, a closure flap mounted on the outside panel of the envelope compartment adapted to 45 close, selectively, the envelope compartment and the paper-receiving panel selectively, and paper fastening means secured to the paper-receiving panel 50 adjacent to an end thereof enabling the securing of papers in flat position upon the panel, the papers being intermediate the panel and envelope compartment when the paper-receiving panel is closed.

CHARLES I. SCHWINGER.
